UNITED STATES PATENT OFFICE.

EDWARD N. ROWELL AND JAMES LITTLE, OF BATAVIA, NEW YORK,
ASSIGNORS TO E. N. ROWELL COMPANY, OF BATAVIA, NEW
YORK.

PAPER-BOX MACHINE.

No. 844,190.

Specification of Letters Patent.

Patented Feb. 12, 1907.

Application filed May 15, 1894. Serial No. 511,314.

To all whom it may concern:

Be it known that we, EDWARD N. ROWELL and JAMES LITTLE, citizens of the United States, residing at Batavia, in the county of Genesee and State of New York, have invented a new and useful Improvement in Paper-Box Machines, of which the following is a specification.

This invention relates to a machine for making paper boxes composed of a cylindrical body and a circular head which are united by a band of gummed paper wound around the body and the head.

One object of our invention is to produce a machine in which the feeding of the heads and the winding of the bands are effected automatically.

Another object of our invention is to provide simple means for turning the edges of the bands inwardly over the edges of the body in an expeditious manner.

In the accompanying drawings, consisting of eleven sheets, Figure 1 is a front elevation of our improved box-making machine. Fig. 2 is a fragmentary top plan view. Figs. 3 and 4 are vertical longitudinal sections in lines 3 3 and 4 4, Fig. 2, respectively, looking rearwardly. Fig. 5 is a fragmentary end view of the cam and connecting-rod for actuating the band-cutter. Fig. 6 is a vertical longitudinal section, on an enlarged scale, of the band-gripper and connecting parts. Fig. 7 is a horizontal section in line 7 7, Fig. 6. Fig. 8 is a vertical longitudinal section in line 8 8, Fig. 2, looking forward. Fig. 9 is a cross-section in line 9 9, Fig. 2. Fig. 10 is a cross-section, on an enlarged scale, of the band turning in guide-rails mounted on the carrying-plate. Fig. 11 is a fragmentary side elevation, on an enlarged scale, of the gripper on the head-carrying arm. Fig. 12 is a vertical section in line 12 12, Fig. 11. Fig. 13 is a longitudinal section, on an enlarged scale, of one of the mandrels for supporting the body of the box. Fig. 14 is a front elevation thereof. Fig. 15 is a horizontal section, on an enlarged scale, in line 15 15, Fig. 4. Fig. 16 is a vertical transverse section, on an enlarged scale, in line 16 16, Fig. 2. Fig. 17 is a fragmentary sectional view, on an enlarged scale, showing the yielding connection between the sliding rod supporting the holding-disk and its actuating-lever. Fig. 18 is a sectional elevation, on an

enlarged scale, of the elbow-lever for actuating the head-feeding plate. Fig. 19 is a top plan view of the same. Fig. 20 is a vertical longitudinal section, on an enlarged scale, in line 20 20, Fig. 2. Fig. 21 is a vertical longitudinal section, on an enlarged scale, in line 21 21, Fig. 9. Fig. 22 is a vertical cross-section, on an enlarged scale, in line 22 22, Fig. 3. Fig. 23 is a longitudinal section in line 23 23, Fig. 22. Fig. 24 is a perspective view of the swivel-ring for supporting the rollers which finish the edge of the box. Fig. 25 is a fragmentary sectional elevation, on an enlarged scale, showing the actuating-arm of the band-gripper and the cam for opening the gripper to receive the band. Fig. 26 is a similar view showing the cam for opening the gripper to release the band. Fig. 27 is a longitudinal section showing a modification of the mandrel for supporting the body of the box. Fig. 28 is a front view of the same. Fig. 29 is an end elevation of our improved box-making machine viewed from the left-hand side. Fig. 30 is a sectional elevation of that portion of the machine whereby the margin of the band is turned inwardly over the edge of the body. Fig. 31 is a horizontal section in line 31 31, Fig. 30, looking downwardly. Fig. 32 is a horizontal section in line 32 32, Fig. 30, looking upwardly. Fig. 33 is a sectional inside view of the cam-wheel whereby the finishing-head and magazine are operated. Fig. 34 is an elevation of the band-turning-in mechanism viewed from the side opposite to that shown in Fig. 29. Fig. 35 is a rear elevation thereof.

Like letters of reference refer to like parts in the several figures.

A represents the stationary base or main frame of the machine, and B represents a horizontally - reciprocating slide or table which is guided in ways c c, arranged on the horizontal upper portion of the frame.

D represents a gear-rack secured lengthwise to the under side of the reciprocating table, and D' represents a stationary gear-rack secured lengthwise to the lower portion of the main frame vertically in line with the table gear-rack D.

E represents a vertical gear-wheel which engages with the movable and stationary gear-racks and is journaled upon a horizontal wrist-pin e.

F represents a counter-shaft journaled

transversely in bearings on the lower portion of the main frame and provided centrally below the reciprocating table with a crank f . This crank is connected with the wrist-5 pin e by a connecting-bar f' . Upon revolving the counter-shaft the gear-wheel E is rolled back and forth on the stationary gear-rack by the connecting-bar and crank, which causes the movable gear-rack and the table 10 connected therewith to be reciprocated forwardly and backwardly a distance equal to twice the throw of the crank in a well-known manner.

F' represents the main shaft journaled 15 transversely in bearings arranged on the main frame and provided with a small gear-wheel F^2 , which meshes with a large gear-wheel F^3 , mounted on the rear end of the counter-shaft, whereby the latter is driven.

20 G represents a mandrel-frame which carries the mandrels for supporting the cylindrical bodies of the boxes. This mandrel-frame is arranged above the reciprocating table and consists of a hub g and two pairs of 25 bearings $g^1 g^2$, arranged on diametrically opposite sides of the hub. The mandrel-frame is provided at its front end with a transverse shaft g^3 , which is journaled horizontally in a bearing formed in the upper 30 end of a standard g^4 , secured upon the main frame.

H represents mandrels upon which the cylindrical bodies H' of the boxes are placed by the operator, as shown in Figs. 13 and 14. 35 Each of these mandrels preferably consists of a circular head h , having an annular flange on its rear end and a split mandrel-ring h' , surrounding the head and loosely connected therewith by rivets or bolts h^2 , secured to inwardly-projecting ears h^3 on the split ring and passing loosely through openings h^4 , formed in the head. The peripheral front portion of the mandrel-head and the contiguous inner face of the mandrel-ring are 40 tapered so that upon sliding the ring upon the head in one direction the ring will be spread, while upon sliding the ring in the opposite direction the ring will be contracted. In the normal position of the mandrel-ring 45 it is arranged on the front portion of the mandrel-head and contracted sufficient to permit the circular body of the box to be easily placed upon the same. Upon moving the mandrel-ring backwardly on the head 50 the ring is spread, thereby gripping the body of the box and holding the same against turning on the mandrel. Each mandrel-head is secured to the rear end of a short horizontal shaft h^5 , which is journaled in a 55 pair of the bearings of the mandrel-frame. Upon turning the mandrel-frame either of its mandrels can be brought into an operative or inoperative position over the reciprocating table.

60 The construction of the mandrels may be

modified, as shown in Figs. 27 and 28. In these figures H^2 represents the annular mandrel-head, and H^3 holding-jaws arranged to slide in radial ways H^4 , formed in the face of the mandrel-head and extending inwardly 70 from the periphery thereof. The outer ends of these jaws are curved, so that when they are moved outwardly they close the outer ends of the ways and complete the peripheral face of the mandrel. 75

H^5 represents a shifting cone arranged axially in a correspondingly-shaped opening formed in the mandrel-head and provided at its rear end with a shank H^6 , arranged to slide in a socket H^7 , formed in the mandrel-head. The shifting cone is normally held in a forward position by a spring H^8 , arranged in the socket H^7 , and bearing against the rear end of the shank. 80

H^9 represents knuckles formed on the inner ends of the sliding jaws and engaging with undercut grooves H^{10} , formed in the tapering side of the shifting cone at an angle to the line of movement of the sliding jaws. In the normal forward position of the shifting cone the jaws are drawn inwardly, so that their outer ends recede from the periphery of the mandrel. Upon placing the body of the box upon the periphery of the mandrel it tends to flatten across the spaces at the outer 90 ends of the ways H^4 . Upon pressing the cone into the mandrel-head the jaws are moved outwardly, so that their outer ends are flush with the periphery of the mandrel-head, thereby pressing out the flattened 100 portions of the body and holding the same tightly upon the mandrel. 95

h^6 represents gear-wheels secured to the mandrel-shafts between the bearings of the mandrel-frame and adapted to engage alternately with a gear-rack h^7 , secured lengthwise upon the reciprocating table in line with the said gear-wheels. During the forward movement of the table the mandrel-frame is so turned that neither of the mandrel gear-wheels is in engagement with the gear-rack h^7 . When the reciprocating table has reached the limit of its forward movement, the mandrel-frame is turned so that one of its gear-wheels stands in the path of the gear-rack h^7 , which causes the latter during the subsequent backward movement of the table to engage with said gear-wheel and rotate the mandrel connected therewith. In order to insure the proper engagement of the 110 mandrel gear-wheels with the mandrel gear-rack, the latter is provided at its rear end with a yielding gear-section h^8 , which forms a rearward extension of the mandrel gear-rack and is yieldingly supported by a 115 spring h^9 , secured to the table. If the relative position of the mandrel gear-wheel and the yielding gear-section is such that the latter will not mesh with said gear-wheel upon 120 striking the same, the gear-section will be 125 de- 130

flected until the gear-wheel has shifted sufficiently to cause it to mesh properly with the gear-section when the latter resumes its normal position.

5 I represents a ratchet-disk whereby the mandrel-frame is intermittently rotated and which is secured to the front end of the shaft supporting the mandrel-frame.

i represents an oscillating ratchet-arm 10 whereby the ratchet-disk is turned and which is preferably pivoted concentrically on a hub formed on the front end of the ratchet-disk. The free end of the ratchet-arm is provided with a pawl i', which engages with one of four notches i'', formed equidistant in the periphery of the ratchet-disk.

i''' represents a detent-pawl pivoted with its lower end on the main frame and engaging with its free hooked end in the notch following 20 the notch with which the pawl of the ratchet-arm engages. The hook of the detent-pawl is yieldingly held in engagement with the notches of the ratchet-disk by a spring i''. During the last portion of the 25 backward movement of the ratchet-arm the latter engages with a pin i''' on the detent pawl and forces the hook of the detent-pawl out of the notch, which permits the pawl of the ratchet-arm to enter the notch from 30 which the detent-pawl has just been removed, and during the subsequent forward movement of the ratchet-arm the ratchet-disk is moved forward a quarter-turn. When the 35 ratchet-disk has completed a quarter-turn, the detent-pawl enters the next succeeding notch and holds the mandrel-frame in position.

i'' is a detent-spring secured with one end to the main frame and engaging with its 40 other end in one of four equidistant notches i'', formed in the rear side of the ratchet-disk. This detent-spring holds the ratchet-disk against displacement during the time that both the actuating and detent pawls are 45 connected from the ratchet-disk.

i'' represents a grooved mandrel-cam which is secured to the front end of the counter-shaft and whereby an oscillating motion is imparted to the ratchet-arm for turning the 50 mandrel-frame.

i'' represents a connecting-rod pivoted at one end to the ratchet-arm and provided at its opposite end with a roller i'''', which runs in the groove of the cam i''. This connecting 55 rod preferably straddles the counter-shaft, whereby it is guided in its movements. During each backward and forward movement of the ratchet-arm the mandrel-frame is turned one quarter-revolution. The groove in the 60 mandrel-cam is so constructed that one of the mandrels is held in its lower operative position over the reciprocating table during the entire backward movement of the latter, and during the next forward movement of 65 the table the mandrel-frame is turned two

quarters, so that the other mandrel is brought to the lower operative position at the end of the forward movement of the table.

J represents a cylindrical magazine secured lengthwise to the rear side of the main frame 70 and adapted to carry a supply of circular heads for the boxes. The heads are introduced into the rear portion of the magazine through an opening j in the top thereof and are constantly pressed forward by a follower j'. The latter is provided with a rod j'', passing through the rear end of the magazine, and moved forwardly by a weight j''', which is connected with the rod by a cord j'', passing around a roller j''' on the rear end of the magazine. 80

K represents a vertically-sliding feed-plate which moves transversely across the front end of the magazine and successively delivers the heads through an opening k in the 85 top of the magazine. Every time the feed-plate crosses the magazine its upper edge strikes the lower edge of the foremost head and pushes the same upwardly through the discharge-opening. 90

k' is an oscillating elbow-lever whereby an intermittently-reciprocating movement is imparted to the feed-plate and which is pivoted to the main frame. The upper arm of the elbow-lever consists of a rigid section k'' 95 and a yielding section k''', pivoted to the rigid section. The yielding section is free to swing downwardly on the rigid section, but is limited in its upward movement thereon by a stop k'', against which the yielding section is normally held by a spring k'''. The yielding section of the elbow-lever is connected with the lower portion of the feed-plate 100 by a link k''. If from any cause the upward movement of the feed-plate should be arrested—as, for instance, clogging of the head-discharge opening—the yielding section of the elbow-lever permits the remaining portion of said lever, which latter is moved positively, to continue its move- 110

ment independent of the yielding section, thereby preventing injury to the elbow-lever and connecting parts. The lower arm of the elbow-lever is provided with a pin k'', which engages in the peripheral groove of a cam k''', 115 whereby the elbow-lever is actuated. This cam is mounted on a cam-shaft k'', journaled lengthwise in bearings secured to the lower rear portion of the main frame.

L represents a carrying-arm whereby the heads are carried successively from the magazine to the mandrels. This arm is provided at its free end with a gripper consisting of a depending rigid jaw l and a movable jaw l', pivoted with its upper end to the carrying-arm. The jaws of the gripper are provided in their inner or opposing faces with vertical grooves l'' for the reception of the marginal portion of the heads. The gripper-jaws are yieldingly held together, so that the space 120 125 130

between them is less than the diameter of a head, by a spring l^3 , secured with one end to the movable jaw and bearing with its other end against the carrying-arm. The fixed 5 end of the carrying-arm is secured to the upper end of a vertical rock-spindle l^4 , which passes through the top of the main frame in rear of the reciprocating table. This spindle is square in cross-section and is arranged in a 10 correspondingly-shaped socket formed lengthwise in a rock-sleeve l^5 , which compels the spindle to oscillate with the rock-sleeve, but permits the spindle to move lengthwise in the same. The rock-sleeve is journaled in 15 an upright bearing l^6 , arranged on the main frame. The lower end of the rock-sleeve is provided with an arm l^7 , which projects rearwardly through an opening in the main frame. l^8 is an elbow-lever pivoted on the 20 rear side of the main frame and connected with its upper arm by a link l^9 to the arm of the rock-sleeve, while its lower arm is provided with a pin or roller which engages with a cam l^{10} on the counter-shaft. The cam l^{10} 25 is so formed that the carrying-arm is oscillated one-quarter of a revolution, whereby the gripper of the latter carries a head from the magazine to the face of the lower operative mandrel and then disengages itself 30 from the head and returns to its former position over the magazine.

M represents a lifting elbow-lever whereby the carrying-arm is raised as it passes back and forth between the magazine and mandrel and which is pivoted on the main frame. 35 One arm of the lifting elbow-lever is provided with a fork m , which engages loosely with a groove-head m' in the lower end of the spindle l^4 , while its other arm is provided with a 40 pin or roller m^2 , which engages with a lifting-cam m^3 , arranged on the cam-shaft. This cam is so formed that it raises the carrying-arm as it oscillates between the magazine and mandrels, thereby enabling the gripper 45 and head to clear the upper parts of the machine. The carrying-arm is provided on its under side adjacent to the spindle with two V -shaped lugs m^4 , which are adapted to engage with one of two pairs of V -shaped 50 notches formed in a cap m^5 , secured to the upper end of the upright bearing l^6 . These lugs and notches assist in centering the carrying-arm when it arrives in its proper position with reference to the magazine or the mandrel. In order to steady the gripper 55 while it holds the box-head in front of the lower mandrel, the rigid arm of the gripper is provided with a guide-pin m^6 , which is adapted to engage alternately with two 60 guide-hooks m^7 , arranged on opposite sides of the mandrel-frame, as shown in Figs. 8 and 21.

N represents a holding-disk whereby the box-heads are held against the lower mandrel preparatory to uniting the same with the

body of the box. This holding-disk is pivoted centrally on the front end of a transverse sliding rod n , which slides in a bracket n' , arranged on the rear portion of the main frame.

n^2 represents a rock-lever whereby the holding-disk is carried toward and from the lower mandrel and which is pivoted on the rear portion of the main frame. The rock-lever is moved forwardly by a cam n^3 on the cam-shaft bearing against the lower arm of said lever and is moved in the opposite direction by a spring n^4 , secured to the main frame and bearing against the upper arm of the rock-lever. The upper arm of the rock-lever is provided with a slot n^5 , Fig. 17, and is secured to the rear end of the sliding rod n by a pin n^6 , passing through said slot.

n^7 is a follower arranged in a socket formed in the rear end of the sliding rod n and pressed against the upper arm of the rock-lever n^2 by a spring n^8 , arranged in said socket. During the forward movement of the rock-lever the holding-disk N moves with the same until it strikes the box-head on the mandrel, when 90 the rock-lever, during the remainder of its forward movement, independent of the holding-disk, compresses the spring n^8 . This yielding connection between the rock-lever and holding-disk permits of a slight variation in the thickness of the box-heads.

O represents a band-supporting rail which is arranged lengthwise underneath and in line with the periphery of the mandrels and upon which is laid the band of paper O' to be wound around the body and the head of the box. The band-rail is secured to a carrying-plate O^2 , which latter is secured to the top of the reciprocating table.

O^2 is a turning-rail arranged on the carrying-plate in rear of the band-supporting rail parallel therewith and separated therefrom by a longitudinal groove O^3 , in which the margin of the box-head runs when the mandrel revolves.

O^4 represents a raised guide-rail arranged along the front side of the band-rail, and O^5 is a similar rail arranged on the rear side of the turning-rail. The rails O^4 and O^5 guide the band of paper as it is delivered upon the supporting-rail O and hold the same in place. As the mandrel carrying the body and head of the box rotates in contact with the band lying on the supporting and turning rails O O^2 that portion of the band resting on the supporting-rail is wound around the body of the box and that portion extending across the groove O^3 and resting on the turning-rail is turned over the margin of the head and against the under side of the latter, so as to connect the body with the head. The rear guide-rail O^5 overhangs the turning-rail, and the latter is adjusted with reference to the band-rail by screws O^6 , arranged in the rear guide-rail and bearing against the rear side

of the turning-rail, as shown in Figs. 9 and 10. The front guide-rail is provided with a base-flange o^7 and is adjustably secured to the carrying-plate by screws o^8 , passing through transverse slots o^9 , formed in the base-flange.

The band of paper is wound upon a supply-roller (not shown in the drawings) from which a sufficient length to encircle the box is unwound at every forward stroke of the reciprocating table by a gripper P , carried by the table and which seizes the end of the band, the portion of the band thus delivered upon the table being severed by a cutter, hereinafter described, preparatory to being wound around the box. This gripper bears against a depressed gripper-face p , Fig. 6, formed on top of the band-rail, and is provided with a depending shank p' , which passes vertically through recesses p^2 p^3 , formed in the band-rail and the carrying-plate, respectively.

p^4 is a rock-shaft whereby the gripper is opened and closed and which is journaled transversely in the carrying-plate and extends from its rear side into the recess p^3 thereof. The inner end of the rock-shaft p^4 is provided within the recess p^3 with a rock-finger p^5 , which is arranged with its free end in a socket p^6 , formed in the shank of the gripper. The gripper rock-shaft is provided at its rear end with a trip-arm g , as shown in Figs. 2 and 7, whereby the gripper is opened and closed. The gripper is yieldingly held in a closed position by a spring q' , secured to the reciprocating table and bearing against a pin q^2 on the trip-arm. The free end of the trip-arm is provided with a lug adapted to engage with primary and secondary trip-cams q^3 q^4 , whereby the gripper is opened for receiving and releasing the band of paper. The primary trip-cam q^3 inclines from its front end upwardly to its rear end and is pivoted at its upper rear end to a bracket q^5 , arranged on the main frame. During the last portion of the backward movement of the reciprocating table the trip-arm rides over the incline of the primary cam and to the top of the bracket q^5 , thereby opening the gripper for receiving the front end of the roll of band-paper. The instant the latter is delivered to the gripper the trip-arm drops over the back of the bracket and the end of the roll of paper is grasped by the gripper. During the forward movement of the reciprocating table the trip-arm engages against the under side of the pivoted primary cam and lifts the latter out of its way without disturbing the gripper, thereby permitting the gripper to maintain a firm hold on the paper during the first portion of its forward movement for unwinding the paper from the roll. The secondary trip-cam q^4 is rigidly secured upon the central portion of the main frame in line with the primary trip-cam and is provided with inclined

front and rear ends. When the reciprocating table has completed about one-half of its forward movement, the cutter severs that portion of the band which has been unwound from the supply-roll, and at the end of the forward movement of the table the rear end of the band is arranged underneath the body and head of the box on the mandrel preparatory to being wound around the same during the subsequent backward movement of the table. When the reciprocating table has completed about one-half of its backward movement, the trip-arm rides over the inclined front side of the secondary trip-cam, which releases the end of the band of paper from the gripper and permits the mandrel to wind the same around the box body and head. After the paper band is released from the gripper the trip-arm drops over the rear side of the secondary trip-cam and again closes the gripper. During the forward movement of the reciprocating table the secondary trip-cam also raises the trip-arm and opens the gripper momentarily; but before this occurs the band of paper has already been severed from the roll of paper, so that no resistance is offered to the forward movement of the severed paper band, and the latter is not withdrawn from the gripper during the momentary opening of the same. If desired, the secondary trip-cam may be of the same construction as the primary trip-cam.

R represents a reciprocating feed-plate, upon which the end of the paper band rests and which slides in a standard r , arranged on the main frame over the receiving end of the reciprocating table. The feed-plate is inclined toward the reciprocating table, and the paper band is guided thereon by guides r' , secured to the feed-plate on opposite sides of the band.

r^2 represents holddown-fingers secured to the feed-plate and bearing upon the band, whereby the band is prevented from rising.

r^3 is a detent-plate whereby the band is held against backward movement on the feed-plate. This detent-plate bears upon the band in rear of the holddown-fingers and is secured to a transverse shaft r^4 , which is journaled in bearings r^5 , arranged on the feed plate. The detent-plate is pressed lightly against the band by a spring r^6 , secured with its ends to the transverse shaft r^4 and one of its bearings. The front end of the paper band projects slightly beyond the front end of the feed-plate when the latter is in its normal backward position. During the last portion of the backward movement of the reciprocating table the feed-plate is moved forwardly and places the end of the paper band between the gripper and the opposing gripper-face.

s represents an oscillating lever whereby a reciprocating movement is imparted to the feed-plate. The lever s is pivoted between

its arms upon a bracket secured to the main frame, and its upper arm s' is connected with the rear portion of the feed-plate by a link s^2 . The lower arm of this lever s is forked or bifurcated and consists of two jaws s^3 s^4 .

s^5 represents a trip-pin secured to the front end of the gear-rack on the under side of the reciprocating table and adapted to engage with the forked lower end of the feed-lever for reciprocating the feed-plate. In the normal position of the feed-plate the lower arm of the feed-lever inclines toward the reciprocating table, with the space between the jaws arranged in line with the trip-pin. During the last portion of the backward movement of the reciprocating table the trip-pin engages with the jaw s^4 of the feed-lever and pushes the lower arm backwardly, which causes the feed-plate connected with the upper arm thereof to be moved forwardly for inserting the end of the band into the gripper. During the first portion of the forward movement of the reciprocating table the trip-pin engages with the jaw s^3 of the feed-lever and returns the same and the feed-plate to their normal positions.

s^6 represents a catch whereby the feed-lever is held in its normal position and which is pivoted to the main frame. This catch is provided with a notch s^7 in its upper side, which receives the jaw s^4 of the feed-lever and is yieldingly held in engagement therewith by a spring s^8 , arranged on the main frame. When the feed-lever is shifted by the trip-pin, the catch s^6 is deflected, but engages again with the feed-lever when the latter resumes its normal position, thereby insuring the proper engagement of the trip-pin with said lever.

T represents a vertically-movable cutter or knife-blade whereby the paper band is cut into proper lengths as the same is drawn over the feed-plate. This cutter is arranged transversely above the feed-plate and is adapted to operate in conjunction with a shearing-face t , formed on the front end of the standard which supports the feed-plate. The cutter is provided at its ends with arms t' , which are secured to a transverse cutter-shaft t^2 , journaled in the standard. One end of the cutter-shaft is provided with a rock-arm t^3 , whereby an oscillating movement is imparted to the cutter.

t^4 is a cam secured to the cam-shaft, and t^5 is a connecting-rod passing through an opening in the top of the main frame and pivotally connected at its upper end to the rock-arm of the cutter-shaft. The lower bifurcated end of the connecting-rod straddles the cam-shaft and is provided with a roller t^6 , which bears against the cutter-cam. The latter is so constructed that it holds the cutter in a raised position during the forward and backward movement of the feed-plate, and when a sufficient length of the paper

band has been drawn over the feed-plate the cutter drops and severs the band. The descent of the cutter is preferably aided by a spring t^7 , secured to the main frame and bearing against a pin t^8 , secured to the rock-arm t^3 . The paper band is gummed on its upper side in any suitable manner before it is carried to the feed-table. The cutter is provided on its front side with a holding-down finger t^9 , which carries the rear end of the severed band downwardly between the guide-rails and prevents the same from becoming displaced.

u u' represent upper and lower burnishing or finishing rollers arranged at right angles to each other and adapted to press the gummed band against opposite sides of the margin of the box-head. The lower roller u' is arranged vertically adjacent to the rear end of the band-sup porting rail, with its rear side in line with the rear side of said rail. The upper roller u is arranged horizontally adjacent to the rear end of the turning rail, with its periphery in line with the front side of said rail.

u^2 represents a swivel collar or ring provided with pins or studs u^3 , upon which the finishing-rollers are mounted. The swivel-collar is pivoted upon a rock-plate u^4 by a longitudinal pin u^5 , so that the collar can turn transversely with reference to the reciprocating table. The rock-plate is pivoted at its ends by transverse screws u^6 upon a U-shaped rock-frame u^7 , so that the plate can swing vertically lengthwise of the reciprocating table. The rock-frame is pivoted with its arms upon opposite sides of the carrying-plate by transverse pivots u^8 , so that it can swing vertically, and is yieldingly held in an elevated position by means of a spring u^9 , bearing with its ends against the top of the reciprocating table and the under side of the cross-bar of the rock-frame. The rock-plate, swivel-collar, and rollers supported thereon are normally held in a forwardly-inclined position by means of a spring u^{10} , connected at one end to the top of the reciprocating table and with its other end to an upwardly-projecting rock-arm u^{11} , formed on one end of the rock-plate. During the last portion of the backward movement of the reciprocating table the mandrel leaves the band-rail and the paper box is brought into engagement with the finishing-rollers. The vertical finishing-roller presses the paper band into the corner between the body and the front marginal portion of the head, while the horizontal roller presses the lower edge of the band against the rear marginal portion of the head.

If the paper box tends to exert a greater pressure upon one finishing-roller than upon the other, that roller with which the box first engages is tilted, thereby carrying the other roller against the box and equalizing the pressure of the finishing-rollers. In order to

press the band properly against the rear side of the box-head, the axis of the horizontal finishing-roller must always be radially in line with the center of the paper box.

5 For this purpose the rock-arm v^{11} projects upwardly sufficiently so that it is struck by the sliding rod supporting the holding-disk, while the reciprocating table is in its backward position, as represented in Fig. 23, thereby causing the finishing-roller to be shifted and held in its proper relative position with reference to the paper box irrespective of the position of the reciprocating table.

15 The mandrel gear-rack is disengaged from the mandrel gear-wheel during the last portion of the backward movement of the reciprocating table, and the mandrel is rapidly rotated several times for the purpose of bringing the entire periphery of the box into engagement with the finishing-roller by mechanism constructed as follows: V, Fig. 9, represents a transverse sliding shaft journaled in a bearing in the lower portion of the mandrel-standard below the mandrel-frame and capable of longitudinal movement in said bearing. This shaft is provided on its rear end with a gear-wheel v' , which is adapted to engage with the gear-wheel of the operative lower mandrel for turning the same after it leaves the mandrel gear-rack. v^2 represents a rock-shaft whereby the sliding shaft is reciprocated lengthwise for the purpose of placing the gear-wheel v' in or out of engagement with the mandrel gear-wheel. This rock-shaft is journaled in bearings v^3 , arranged on the main frame, and provided at its ends with two rock-arms v^4 v^5 . The rock-arm v^4 is provided with a fork v^6 at its upper end, which engages with a grooved collar v^7 on the outer end of the sliding shaft, whereby the latter can be moved lengthwise, but is capable of rotating independent thereof. The rock-arm v^5 is bent inwardly along the right-hand side of the main frame and provided with a roller v^8 . v^9 is a shifting cam secured to the rear end of the reciprocating table and adapted to engage with the arm v^5 of the rock-shaft v^2 during the last portion of the 45 backward movement of the reciprocating table for rocking said shaft and moving the shifting gear-wheel into engagement with the mandrel gear-wheel. After the reciprocating table has completed the first portion of its forward movement the shifting cam v^9 leaves the roller of the rock-arm, when the shifting gear-wheel is disengaged from the mandrel gear-wheel and returned to its normal position by a spring v^{10} , bearing with its 50 ends against the front side of the main frame and the rear side of the rock-arm v^4 . The shifting gear-wheel is rotated constantly at a peripheral speed considerably greater than the lineal speed of the mandrel-rack by 55 means of a sprocket-chain v^{11} running around

a large sprocket-wheel v^{12} on the main shaft and a small sprocket-wheel v^{13} on the sliding shaft.

The operation of uniting the circular body and the head of the box is as follows: During 70 the last portion of the backward movement of the reciprocating table the feed-plate moves forward and feeds the end of the band of paper into the gripper. The latter is now closed, and during the subsequent forward 75 movement of the reciprocating table the paper band is drawn upon the latter, and when a sufficient length has been withdrawn the cutter severs the same. This severed portion of the paper band is now carried forward until its rear end arrives in line with or in rear of the axis of the mandrel. During this forward movement of the reciprocating table the operator places a box-body on the upper mandrel, and the mandrel-frame is 80 then turned automatically, so that the upper mandrel carrying the body will occupy the operative lower position when the reciprocating table reaches the end of its forward movement. The instant the mandrel carrying 85 the box-body arrives in its operative position the carrying-arm places a box-head against the face of the mandrel, and the holding-disk holds the head in place, while the carrying-arm detaches itself from the head 90 and returns to the magazine. During the subsequent backward movement of the reciprocating table the body of the box and the box-head roll over the gummed paper band, thereby picking the same up from the supporting-rail and winding the same around the body and the head. Shortly before the gripper arrives underneath the mandrel during its backward movement with the reciprocating table it opens to permit the front end 95 of the band to be withdrawn from the same and to be wound around the body and head of the box. When the reciprocating table has reached the end of its backward movement, the finishing-rollers engage against the 100 box and press the band smooth, after which the holding-disk is removed and the mandrel-frame is given a quarter-turn, so as to raise the lower mandrel from the band-rail. During the subsequent forward movement the 105 operator removes the finished box and places another body on the upper or idle mandrel. After the band is wound upon the body and head of the box the upper edge of the band is automatically turned inwardly over the upper 110 edge of the body by mechanism which is constructed as follows, and which is illustrated in Figs. 29-35:

W represents a rearward extension of the main frame, provided with a table w and a standard W' on one side of said table.

w' is a magazine-disk which rests upon the table and is mounted on the lower end of a spindle w^2 , journaled with its upper and lower ends in bearings formed, respectively, 130

in an overhanging arm W^2 of the standard and the table w . The magazine is provided with a circular row of pockets w^3 , into which the operator places the wound boxes with the head resting on the table.

w^4 represents a ratchet-lever pivoted loosely upon the upper portion of the spindle and provided with a pawl w^5 , which engages with a ratchet-wheel w^6 , secured to the spindle.

w^7 is an elbow-lever whereby the ratchet-arm is oscillated and which is pivoted at its elbow to the main frame. The upper arm of this elbow-lever is connected with the free end of the ratchet-arm by a link w^8 , while the other arm is provided at its end with a roller w^9 , which engages with a cam-groove w^{10} , formed in a disk or wheel w^{11} , mounted on the main shaft in rear of the standard W' . This cam-groove is so constructed that each revolution of the main shaft turns the magazine-disk the distance between two adjacent pockets.

w^{12} is a detent-pawl which is adapted to engage with notches in the edge of the magazine-disk for holding the table against backward movement. This pawl is secured to the upper end of a vertical rock-spindle w^{13} , journaled in bearings w^{14} on the side of the main frame. The detent-pawl is yieldingly held in engagement with the notches in the magazine-disk by a spring w^{15} , secured with its ends to the rock-spindle and the main frame.

w^{16} represents a tappet formed on the front side of the cam disk or wheel and adapted to strike an arm w^{17} , formed on the rock-spindle w^{13} for throwing the detent-pawl out of engagement with the notches of the magazine-disk while the latter is being moved forward.

X represents a folder-head whereby that portion of the band projecting above the upper edge of the body of the box is turned or bent inwardly over said edge and at right angles thereto. This head is arranged over the magazine in line with the path of the pockets therein and is secured with its upper end to the arm of the standard by means of a hollow shank x' . The under side of the folding-head is provided with an annular groove or folding-face x^2 , which is curved from its outer edge upwardly toward the center thereof.

x^3 represents a plunger whereby the boxes are carried successively from the pockets in the magazine upwardly against the folding-face of the folding-head. This plunger is arranged vertically in line with the folding-head and slides in an opening x^4 , formed in the table in line with the path of the pockets in the magazine. In the normal position of the plunger its top face is arranged flush with or slightly below the top of the magazine-table, which permits the magazine to be turned for bringing one of its filled pockets axially in

line with the plunger and the folding-head. Upon raising the plunger when a filled pocket is arranged in line with the same the plunger lifts the box in said pocket and carries it against the folding-face, which causes the latter to turn the upper edge of the band inwardly over the upper edge of the body and at right angles thereto. This upward movement of the plunger is effected by a cam x^5 , secured to the main shaft and bearing against a roller x^6 on one side of the plunger. After the box is finished the plunger is depressed by a cam x^7 on the main shaft and engaging with a roller x^8 on the opposite side of the plunger.

y represents a cylindrical finishing-head whereby the upper edge of the band is folded and pressed downwardly against the inner side of the body of the box and finished. This finishing-head is arranged to slide vertically within the folding-head and is about equal in diameter to the inner side of the box-body. After the band has been turned inwardly at right angles to the body of the box by the folding-face it is held against the folding-head a sufficient time to permit the finished head to descend and turn the band against the inner side of the body.

y' is a rock-lever whereby the finishing-head is raised and lowered and which is pivoted between its arms upon the upper end of the standard W' .

y^2 represents a rod whereby the rock-lever is connected with the finishing-head and which is arranged in the hollow head and its shank. The lower end of this rod is rigidly secured to the finishing-head, while its upper end is provided with a groove-collar y^3 , with which the fork y^4 on one arm of the rock-lever engages, thereby compelling the rod to move vertically with the rock-lever, but permitting the same to rotate independent of the rock-lever.

y^5 represents a cam-groove formed in the rear side of the cam-disk w^{11} , and y^6 is a rod connected at its upper end with the other arm of the rock-lever and provided at its lower end with a fork y^7 , which straddles the main shaft, and with a roller which engages with the cam-groove y^5 for imparting an oscillating movement to the rock-lever.

y^8 is a spiral groove formed in the rod y^2 , and y^9 is a pin or screw arranged in the hollow shank of the folder-head and engaging with the spiral groove of the rod. Upon raising and lowering the rod the pin engaging with the spiral groove causes the finishing-head to turn as it enters and leaves the box-body, thereby finishing the inner side thereof. After the band has been turned over the body the plunger descends and the box is again lowered into the pocket of the magazine.

z represents an ejector-block whereby the paper box is caused to recede from the finishing and folding heads with the plunger. This block is arranged in a recess z' in the under

side of the finishing-head and is normally projected below the face of said head by a spring z^2 . During the last portion of the downward movement of the finishing-head the ejector-block strikes the bottom of the box and is forced upwardly into the finishing-head. During the descent of the plunger the resistance of the ejector-spring z^2 causes the ejector-block to press the box downwardly and 5 strip it from the finishing and folding heads should it have a tendency to stick thereto. After the finishing-head has been withdrawn from the box the upper annular edge of the latter contracts slightly, so that its internal 10 diameter is somewhat less than that of the finishing-head. The rear cam-groove y^3 of the cam-disk is so constructed that the finishing-head is moved downwardly a second time during the descent of the plunger, during 15 which movement the finishing-head bears against the upper contracted edge of the box and detaches the same from the folding-head if the box is stuck thereto by particles of paste. After the box has been returned to 20 its pocket the magazine is turned so as to bring the next pocket containing an unfinished box in line with the plunger and folding-head. The magazine-table is provided with an opening z^3 in line with the path of the magazine-pockets, which permit the finished boxes 25 to drop out of the pockets.

We claim as our invention—

1. The combination with the movable table or support, of a mandrel movable toward and from said table or support, substantially 30 as set forth.

2. The combination with the reciprocating table, of a mandrel adapted to bear against said table, and a movable frame supporting 35 said mandrel, substantially as set forth.

3. The combination with the reciprocating table, of mandrels adapted to bear successively against said table, and a rotary frame provided with bearings supporting said mandrels, substantially as set forth.

4. The combination with the movable table or support, of a mandrel for receiving the body portion of the box, a frame supporting the mandrel and movable toward and from 50 the table, and a wheel mounted on the shaft of the mandrel and engaging with said table, substantially as set forth.

5. The combination with the movable table, of a rotary frame, shafts journaled in 55 said frame and provided with mandrels adapted to bear against said table, substantially as set forth.

6. The combination with the movable table provided with a gear-rack and the standard arranged adjacent to the table, of a rotary frame pivoted on said standard, shafts journaled in said frame and provided with mandrels adapted to bear against the table and gear-wheels mounted on said shafts and

adapted to engage with said gear-rack, substantially as set forth.

7. The combination with the movable table, of a rotary frame provided with mandrels adapted to bear against the table, a ratchet-wheel connected with said frame and 70 a ratchet-lever provided with a pawl engaging with said ratchet-disk, substantially as set forth.

8. The combination with the movable table, of a rotary frame provided with mandrels adapted to bear against said table, a ratchet-wheel connected with said frame, a 75 detent-pawl engaging with said ratchet-wheel, and a ratchet-lever adapted to engage with the detent-pawl for throwing the 80 same out of engagement with the ratchet-wheel, and provided with a pawl engaging with said ratchet-wheel, substantially as set forth.

9. The combination with the movable table, of a rotary frame provided with mandrels adapted to bear against said table, a ratchet-wheel connected with said frame, a ratchet-lever connected with the ratchet-wheel and a cam for actuating said ratchet-lever, substantially as set forth.

10. The combination with the movable table provided with a fixed gear-rack, of a yielding gear-rack arranged at one end of the fixed gear-rack, a shaft journaled on a frame 95 and provided with a mandrel, and a gear-wheel secured to said shaft and adapted to engage with the fixed and yielding gear-racks, substantially as set forth.

11. In a box-machine, the combination 100 with a horizontal magazine in which the box-heads are adapted to stand on edge, of a vertically-movable feed-plate for successively removing the box-heads from said magazine, a mandrel mounted on a horizontal shaft, 105 and a horizontally-swinging carrier-arm which is provided with means for seizing said box-heads and whereby the latter are conveyed from the magazine to said mandrel, substantially as set forth.

12. The combination with a horizontal magazine adapted to contain the box-heads, of a mandrel mounted on a horizontal shaft, and an oscillating horizontal carrier-arm having depending jaws adapted to grasp the 115 box-heads in said magazine, substantially as set forth.

13. In a box-machine, the combination 120 with a horizontal magazine in which the box-heads are adapted to stand on edge, of a vertically-movable feed-plate for successively removing the box-heads from said magazine, a mandrel mounted on a horizontal shaft and a horizontally-swinging carrier-arm provided with a fixed jaw and an opposing yielding 125 jaw movable toward and from the fixed jaw, substantially as set forth.

14. The combination with the magazine

and the mandrel, of a carrying-arm which carries the box-heads from the magazine to the mandrel, a rock-sleeve, and a spindle supporting the carrying-arm and capable of sliding in said sleeve, but compelled to turn therewith, substantially as set forth.

15. The combination with the magazine and the mandrel, of a carrying-arm which carries the box-heads from the magazine to the mandrel, a rock-sleeve provided with a rock-arm, a spindle supporting the carrying-arm and capable of sliding in said sleeve but compelled to turn therewith, an elbow-lever for rocking said sleeve, an elbow-lever for reciprocating the spindle and cams whereby the elbow-levers are actuated, substantially as set forth.

16. The combination with the magazine, the mandrel and the mandrel-frame, of a carrying-arm which carries the box-heads to the mandrel, and a guide arranged on the mandrel-frame for steadyng the carrying-arm, substantially as set forth.

17. The combination with a magazine which receives a stack of box-heads, of a mandrel adapted to receive the body of the box, a feeder which removes the foremost head from the magazine, a carrier which receives such head from the feeder and conveys the head to the mandrel, and a holding-aisle which removes the head from the carrier and holds the head against the mandrel, substantially as set forth.

18. The combination with the mandrel and the carrier which carries the box-heads to the mandrel, a sliding rod provided at one end with a holding-aisle which is adapted to hold said heads against the mandrel, a rock-lever loosely connected at one end with said sliding rod, a follower arranged upon the sliding rod and yieldingly held against the rock-lever by a spring and a cam whereby the rock-lever is actuated, substantially as set forth.

19. The combination with the band-supporting rail, of a mandrel adapted to bear against said rail, substantially as set forth.

20. The combination with the band-supporting rail, of a mandrel adapted to bear against said rail and a turning-rail arranged adjacent to the supporting-rail, substantially as set forth.

21. The combination with the band-supporting rail, of a mandrel adapted to bear against said rail and a turning-rail made adjustable toward and from the supporting-rail, substantially as set forth.

22. The combination with the band-supporting rail and the mandrel, of a turning-rail arranged adjacent to the supporting-rail and guide-rails arranged on opposite sides of the turning and supporting rails, substantially as set forth.

23. The combination with the mandrel, of

a band-supporting rail and a gripper arranged on said rail, substantially as set forth.

24. The combination with the mandrel and the band-supporting rail, of a rock-shaft provided with a trip-arm, a gripper secured to the rock-shaft and adapted to seize a band of paper, and a trip-cam adapted to engage against the trip-arm for opening the gripper, substantially as set forth.

25. The combination with the mandrel and the band-supporting rail provided with a gripping-face, a rock-shaft provided with a trip-arm, a gripper secured to the rock-shaft, a spring whereby the gripper is held against the gripping-face, a movable trip-cam adapted to engage with the trip-arm and capable of moving in one direction to clear the trip-arm but held against movement in the opposite direction for actuating the trip-arm, substantially as set forth.

26. The combination with the mandrel and the band-supporting rail provided with a gripper, of a band-feeding plate adapted to move toward and from the gripper, substantially as set forth.

27. The combination with the mandrel and the movable band-supporting rail provided with a gripper, of a movable feed-plate and intermediate mechanism connecting the feed-plate with the band-supporting rail, substantially as set forth.

28. The combination with the mandrel, the reciprocating table provided with a pin and the band-supporting rail provided with a gripper, of a movable feed-plate for feeding the band to the gripper, a rock-lever connected at one end with said feed-plate, and adapted to engage its opposite end with said pin and a catch for holding the rock-lever in its normal position, substantially as set forth.

29. The combination with the mandrel, the reciprocating table, and the band-supporting rail provided with a gripper, of a movable feed-plate whereby the band is fed to the gripper, a rock-lever having one of its arms connected with the feed-plate and having its other arm provided with a fork, a pin arranged on the reciprocating table and adapted to engage with said fork for actuating the rock-lever, and a pivoted catch having a notch engaging with said fork for holding the rock-lever in its normal position, substantially as set forth.

30. The combination with the mandrel and the band-supporting rail provided with a gripper, of a movable feed-plate adapted to feed the band to said gripper and a detent-plate adapted to bear upon the band, substantially as set forth.

31. The combination with the mandrel and the band-supporting table provided with a gripper, of a movable feed-plate whereby

the band is fed to the gripper, a detent-plate pivoted on the feed-plate and a spring whereby the detent-plate is yieldingly held against the band, substantially as set forth.

5 32. The combination with the band-supporting rail provided with a gripper, of a feed-plate for delivering the band to the gripper, a cutter for severing the band, and a mandrel bearing on said supporting-rail, substantially as set forth.

15 33. The combination with the mandrel and the band-supporting rail provided with a gripper, of a feed-plate for delivering the band to said gripper, a cutter for severing the band arranged adjacent to the feed-plate, a rock-shaft supporting the cutter and provided with a rock-arm and a cam connected with said arm for actuating the cutter, substantially as set forth.

20 34. The combination with the mandrel and the band-supporting rail provided with a gripper, of a feed-plate for delivering the band to said gripper, a cutter for severing the band arranged adjacent to the feed-plate and a holding-finger whereby the band is guided and held upon the supporting-rail, substantially as set forth.

30 35. The combination with the mandrel and the band-supporting rail, of a finishing-roller adapted to press the band against the body and the head of the box, substantially as set forth.

35 36. The combination with the mandrel, of a pivoted swivel-ring and finishing-rollers pivoted on said ring, substantially as set forth.

40 37. The combination with the mandrel, of a pivoted supporting-plate, a swivel-ring pivoted on said plate and finishing-rollers pivoted on the swivel-ring, substantially as set forth.

45 38. The combination with the mandrel, of a pivoted frame, a supporting-plate pivoted on said frame, a swivel-ring pivoted on said plate, and finishing-rollers pivoted on said ring, substantially as set forth.

50 39. The combination with the mandrel, of a pivoted frame, a spring for yieldingly holding the frame in a raised position, a supporting-plate pivoted on the frame, a swivel-ring pivoted on the supporting-plate, finishing-rollers pivoted on the swivel-ring and a stop for shifting the position of the finishing-rollers, substantially as set forth.

55 40. The combination with the mandrel and the sliding rod provided with a holding-disk, of a supporting-plate provided with finishing-rollers and an arm formed on the supporting-plate and adapted to engage with the sliding rod for shifting the finishing-rollers, substantially as set forth.

60 41. The combination with the band-supporting rail, the finishing-roller and the rotary mandrel adapted to engage alternately

with the rail and the roller, of driving mechanism adapted to increase the rotary movement of the mandrel when the latter engages with the finishing-roller, substantially as set forth.

65 42. The combination with the band-supporting rail, the finishing-roller and the rotary mandrel, of a driving-shaft adapted to be coupled with the mandrel when the latter engages with the finishing-roller, substantially as set forth.

70 43. The combination with the band-supporting rail, the finishing-roller and the rotary mandrel provided with a gear-wheel, of a movable gear-rack adapted to engage with the mandrel gear-wheel when the mandrel engages with the band-supporting rail, and a driving gear-wheel adapted to engage with the mandrel gear-wheel when the mandrel engages with the finishing-roller, substantially as set forth.

75 44. The combination with the band-supporting rail, the finishing-roller and the rotary mandrel provided with a gear-wheel, of a movable gear-rack adapted to engage with the mandrel gear-wheel when the mandrel engages with the band-supporting rail, a driving gear-wheel adapted to engage with the mandrel gear-wheel when the mandrel engages with the finishing-roller, and a longitudinally-movable shaft carrying the driving gear-wheel, substantially as set forth.

80 45. The combination with the band-supporting rail, the finishing-roller and the rotary mandrel provided with a gear-wheel, of a movable gear-rack adapted to engage with the mandrel gear-wheel when the mandrel engages with the band-supporting rail, a driving gear-wheel adapted to engage with the mandrel gear-wheel when the mandrel engages with the finishing-roller, a longitudinally-movable shaft carrying the driving gear-wheel, and a cam adapted to move the shaft lengthwise, substantially as set forth.

85 46. The combination with the folding-head provided with a folding face or cavity, of a plunger whereby the box is carried against said face for partly folding the band over the edge of the box-body, and a movable finishing-head constructed to enter the box-body and adapted to fold the partly-turned band against the inner side of the box-body, substantially as set forth.

90 47. The combination with a hollow folding-head provided with a folding face or cavity, of a plunger whereby the box is carried against said face for partly folding the band over the edge of the box-body, and a finishing-head arranged to move in the hollow head toward and from said plunger and constructed to enter the box-body, for folding the partly-turned band against the inner side of the box-body, substantially as set forth.

95 48. The combination with the folding-head provided with a folding-face, of a plunger

whereby the box is carried against said face for turning the band over the edge of the box-body, a finishing-head whereby the band is turned against the inner side of the box-body 5 and actuating mechanism whereby a combined reciprocating and rotary movement is imparted to the finishing-head, substantially as set forth.

49. The combination with the folding-head

10 provided with a folding-face, of a plunger whereby the box is carried against said face for turning the band over the edge of the box-body, a finishing-head arranged in the folding-head and adapted to turn the band against 15 the inner side of the box-body, a longitudinally-movable rod connected with said finishing-head and provided with a spiral groove and a stationary pin engaging with said groove, substantially as set forth.

20 50. The combination with the folding-head provided with a folding-face, of a plunger whereby the box is carried against said face for turning the band over the edge of the box-body, a finishing-head arranged in

25 the folding-head and adapted to turn the band against the inner side of the box-body, a longitudinally-movable rod connected with said finishing-head and provided with a spiral groove, a stationary pin engaging with 30 said groove, a rock-lever connected with said rod, and cams for actuating the plunger and the rock-lever, substantially as set forth.

51. The combination with the folding-head and the plunger whereby the boxes are 35 carried against the folding-head for turning the band over the edge of the body, of a movable finishing-head arranged within the folding-head and adapted to turn the band against the inner side of the body, and a

40 spring-pressed ejector arranged in the face of the finishing-head, substantially as set forth.

52. The combination with the reciprocating table, of a mandrel for receiving the body portion of the box, a frame supporting 45 the mandrel and made movable toward and from the table, and a friction-wheel mounted on the shaft of the mandrel and running in contact with the table, substantially as set forth.

50 53. The combination with a reciprocating table having a band-supporting rail and a wheel-operating rail, of a rotary frame, shafts journaled in said frame and provided with mandrels adapted to bear against said 55 band-supporting rail, and wheels mounted on said shafts and adapted to bear against said operating-rail, substantially as set forth.

54. The combination with the mandrel, of 60 a carrying-head adapted to carry the bottom

heads of the box to the mandrel, and a holding-disk whereby the bottom head is removed from the carrying-head and held against the mandrel, substantially as set forth.

65

55. The combination with the reciprocating table and the mandrel, of a band-supporting rail arranged on said table in line with the mandrel, substantially as set forth.

56. The combination with the reciprocating table and the mandrel, of a band-supporting rail arranged on said table, and a turning-rail arranged adjacent to the band-supporting rail, substantially as set forth.

57. The combination with the reciprocating table and the mandrel, of a band-supporting rail arranged on said table, and a turning-rail made adjustable toward and from the band-supporting rail, substantially as set forth.

75

58. The combination with the reciprocating table and the mandrel, of a band-supporting rail arranged on said table, a turning-rail arranged adjacent to the band-supporting rail, and guide-rails arranged on opposite sides of said turning and band-supporting rails, substantially as set forth.

85

59. The combination with the reciprocating table and the mandrel, of a band-supporting rail arranged on said table, and a gripper arranged on said band-supporting rail, substantially as set forth.

90

60. The combination with the reciprocating table and the mandrel, of a band-supporting rail arranged on said table, a rock-shaft journaled on the table, and provided with a trip-finger, a gripper secured to the rock-shaft and adapted to seize the band of paper, and a trip-block adapted to engage against the finger of the rock-shaft for opening the gripper, substantially as set forth.

95

61. The combination with the mandrel and the reciprocating table provided with a gripper, of a band-feeding table movable toward and from the gripper, substantially as set forth.

105

62. The combination with the reciprocating table carrying a gripper, of a feed-table for delivering the band upon the reciprocating table, a cutter for severing the band, arranged in front of the feed-table, and a mandrel running in contact with the reciprocating table, substantially as set forth.
